UNITED STATES PATENT OFFICE.

ALBERTA C. ELLIOTT, OF RINCON, NEW MEXICO.

CLOSURE FOR RECEPTACLES.

1,159,198.

Specification of Letters Patent.

Patented Nov. 2, 1915.

Application filed February 4, 1914. Serial No. 816,655.

To all whom it may concern:

Be it known that I, ALBERTA C. ELLIOTT, a citizen of the United States, residing at Rincon, in the county of Dona Ana and State of New Mexico, have invented new and useful Improvements in Closures for Receptacles, set forth in the following specification.

The invention relates to an improvement in sifters and particularly to a cut off for closing the delivery end of the sifter when necessary to prevent waste of the material and for other advantages.

The main object of the present invention is the provision of a cut off including hingedly connected leaves adapted to be pivotally supported upon the bottom of the sifter body and to be operable to or from a closed position to seal or open the bottom of the sifter.

The invention in the preferred form of details will be described in the following specification, reference being had particularly to the accompanying drawings, in which:—

Figure 1 is a bottom plan of the improved sifter, the leaves being shown closed. Fig. 2 is a similar view, the leaves being shown open. Fig. 3 is a section on line 3—3 of Fig. 1.

In carrying out the present improvement, I secure upon the bottom of the ordinary hand sifter 1 a guide ring 2, said ring being secured at diametrically opposite points by rod connections at 3, whereby the rib is spaced from the proximate edge of the sifter body, as shown. Duplicate semi-circular lips 4 are pivotally supported upon one of the rod connections 3, the mounting of the lips presenting their diametric edges in adjacent relation, so that when the lips are closed, they will overlap each other and completely conceal the bottom of the sifter proper. Remote from their pivotal mounting the lips are cut away at 5 to permit their passing the connection 3 opposite their pivot. Each leaf is provided with a projecting handle portion 6, so arranged that when the lips are closed, the handle portions are in

spaced relation, whereby the leaves may be opened by simply pressing the handle portions together.

A metallic ring 8 is secured within the body 1 of the sifter proper below the screen therein, the edge of said ring being adapted to be projected into a plane coincident with the upper surface of the leaves 4, whereby the ring may act as a scraper to remove all material from the surface of the lips in the opening operation of the latter.

The invention is particularly useful for sifters of the type with which it is shown, as in the use of such sifters the material is generally poured or dumped into the sifter and the latter transported to a table or other support for the pan into which the material is to be sifted. During this transportation there is frequently considerable leakage of the material which with the present improvement is impossible. Furthermore, the present improvement permits the sifter to be used as a positive measuring vessel, it being obvious that with the leaves in closed position, a closed receptacle is provided which can be used for measuring quantities of material.

What is claimed is:—

The combination with a receptacle, of rod connections secured to the bottom thereof at diametrically opposite points, an annular ring carried by the rod connections and disposed below and in spaced relation with the bottom of the receptacle, lips pivotally mounted upon one of the rod connections and movable between the guide ring and the bottom edge of the receptacle, said lips being movable in opposite directions to open or close the bottom of the receptacle, the meeting edges of the lips being formed to overlap when in closed position to maintain a tight connection for the bottom of the receptacle.

In testimony whereof, I affix my signature in presence of two witnesses.

ALBERTA C. ELLIOTT.
